UNITED STATES PATENT OFFICE.

LOUIS SOUTHER, OF SPRINGFIELD, ILLINOIS.

DESIGN FOR A BADGE.

SPECIFICATION forming part of Design No. 15,481, dated October 21, 1884.

Application filed July 11, 1884. Term of patent 3½ years.

To all whom it may concern:

Be it known that I, LOUIS SOUTHER, a citizen of the United States, residing at Springfield, in the county of Sangamon and State of Illinois, have invented and produced a new and original Design for a Badge, of which the following is a specification, reference being had to the accompanying engraving, forming part thereof.

10 The illustration is a front view of my newly - designed badge, this single view being deemed sufficient to fully illustrate my design.

The leading feature of my design is a hel-

met with a white plume and a cartridge-box, substantially as represented in the engraving. 15

The cartridge-box shows letters and an inscription.

I claim—

The design for a badge herein shown and described, the same consisting of a helmet 20 with plume and cartridge-box.

LOUIS SOUTHER.
